(57) **CLAIM**

The ornamental design for a display screen with graphical user interface, as shown and described.

DESCRIPTION

The single FIGURE is a front view of a display screen with graphical user interface.

The broken line showing of the display screen illustrates the environment of the claimed design and forms no part thereof. The broken line showing of portions of the graphical user interface illustrates portions of the graphical user interface which form no part of the claimed design.

1 Claim, 1 Drawing Sheet
